UNITED STATES PATENT OFFICE.

CHARLES GARDNER, OF SAN DIEGO, CALIFORNIA.

RAILWAY-CROSSING ATTACHMENT.

1,263,549.

Specification of Letters Patent. Patented Apr. 23, 1918.

Application filed March 1, 1917. Serial No. 151,872.

To all whom it may concern:

Be it known that I, CHARLES GARDNER, a citizen of the United States, residing at San Diego, in the county of San Diego and State of California, have invented certain new and useful Improvements in Railway-Crossing Attachments, of which the following is a specification.

My invention relates to an attachment to be used at each of the joints of a railway crossing, more particularly street railways, for reducing to a minimum the jar and noise usually accompanying a car when passing over a crossing, and the objects of my invention are; first, to provide an attachment which will reduce to a minimum the noise caused by the car wheels striking the open joints of a railway crossing; second, to provide an attachment of this class which will reduce to a minimum the jar to the car and passengers in passing over a crossing; third, to provide an attachment of this class which is positioned at each of the joints and so arranged as to carry the face of the wheel over the open joint by supporting the wheel on the flange thereof; fourth, to provide an attachment of this class which may be readily placed in position for use in connection with the ordinary or conventional railway crossing now in use or may be placed in said crossing when said crossing is constructed; and; fifth, to provide an attachment of this class which is very simple and economical of construction, durable, easy to install, will not readily deteriorate or get out of order and is easily repaired.

With these and other objects in view, as will appear hereinafter, my invention consists of certain novel features of construction, combination and arrangement of parts as will be hereinafter described in detail and particularly set forth in the appended claims, reference being had to the accompanying drawings and to the characters of reference thereon, which form a part of this specification in which:

Figure 1 is a top or plan view of a joint of a street railway crossing of the conventional type shown by dotted lines and showing by solid lines my attachment positioned in connection therewith ready for use. Fig. 2 is a side view thereof and showing by dotted lines the position of the car wheels when passing over the joint in both directions. Fig. 3 is a top view of the cap member of my attachment. Fig. 4 is a side ele-

vational view thereof and Fig. 5 is a side elevational view of the attachment in a slightly modified form from that of the other views of the drawing.

60

Similar characters of reference refer to similar parts throughout the several views.

The support 1 and cap 2 constitute the principal parts of my attachment.

The support 1 is a cross shaped metallic piece, the members thereof being of suitable thickness to fit snugly into the open joints between the different rail members as shown best in Figs. 1 and 2 of the drawings, and each member on the top surface is provided with a straight flat surface of sufficient length to support the car wheels on the flange so that in approaching and passing the joint the face of the wheel is carried over the joint and any flattened end of the rail, say two or three inches on each side of the joint, and the top surface of this flat portion is of sufficient height relatively to the top of the rails at the joint so that when the wheel flange rests thereon the face of the wheel will be raised approximately 1/16 of an inch above the top of the rail so that the wheel is carried on the flange for approximately eight inches over the joint and flattened end of the rails adjacent the joint. 80

The top surface of each of the members is beveled at 1° at their outer ends for providing a gradual approach for the wheel. The lower surface of the support 1 rests upon the plate to which the rails are secured in the ordinary or conventional type of crossing, portions being cut away as shown at 1° to permit a fit around the edge of the rail flange where said support engages said rail flange. In the preferred construction shown in Figs. 1, 2, 3 and 4 of the drawings the top of the support 1 is covered with a cap which conforms to the top of the support 1 and the extended ends 2^a are bent down against the ends 100

of said support and it is secured thereto by means of tap bolts 2^b which are screwed into tapped holes in each member of the support 1 through oblong holes 2^c shown best in Fig. 4 which permits the raising and lowering of the cap relatively to the support 1 within the limits of said oblong hole 2^c. The principal object of the cap 2 is to permit adjustment of the upper surface of the attachment so that it may be easily 110 kept the proper height to carry the wheel over the joint with the greatest efficiency,

as it is obvious that this cap piece may be shimmmed up relatively to the support 1 as desired, and the bolts 2^b tightened, holding the cap rigidly in position. This cap 2 may 5 be tempered to suit, thus making it wear longer. When the cap 2 is used the top surface of the cap is positioned at the same height as the top surface of the support is when the cap is not used in the structure 10 shown in Fig. 5 of the drawings. The attachment is placed in position by being forced down at the joint between the several rail members, it being understood that slight fitting may be required when placing to accomplish the best results.

Though I have shown and described a particular construction, combination and arrangement of parts and a slight modification thereof, I do not wish to be limited 20 to this particular construction, combination and arrangement and such modifications thereof, but desire to include in the purview of my invention the construction, combination and arrangement substantially 25 as set forth in the appended claims.

It is obvious that with this construction there is provided an attachment which may be readily secured in position at each of the open joints of a railway crossing where- 30 by the wheel will be raised by the flange riding upon the attachment raising the face of the wheel sufficiently to pass the joint and flattened end of the rails without any appreciable noise or jar, as the beveled ends 35 provide for a gradual approach and recession, it being here noted that the raising of the wheel, if any, is to be so slight as not to be noticeable, that the attachment is very simple and economical of construction, easy 40 to install, will not readily deteriorate and in case of wear may be shimmmed up either by placing thin metallic plates between the support 1 and the cap 2 and securing said cap in position by means of the bolts 2^b 45 or by shimmming up the support relatively to

the supporting plate if the modified form of construction shown in Fig. 5 is used; also that the cap may be turned to a different position on the support in case of uneven wear by reason of more traffic in one direc- 50

Having thus described my invention, what I claim as new and desire to secure by Letters Patent is:

1. In an attachment of the class de- 55 scribed, a cross shaped member provided with a smooth upper surface and adapted to fit into the open space between the several rail members in the joint of a railway crossing of suitable height to engage the flange 60 of the car wheel and carry the face of the car wheel over the open joint of the crossing, each member of said cross provided with a beveled, smooth, upper surface portion of full width providing an approach 65 and recession of the car wheel over the joint, and means for readily adjusting the height of said attachment relatively to the top of the adjacent rail members, whereby, 70 said attachment may be readily readjusted to take up the wear thereon:

2. In an attachment of the class de- 75 scribed, a cross shaped rigid member provided with a smooth upper surface and adapted to fit tightly and securely into the open space between the several rail mem- 80 bers in the joint of a railway crossing each member of said cross provided with a beveled, smooth, upper surface portion and a cross shaped bearing plate adjustably secured thereto, each member thereof pro- 85 vided with a beveled, smooth, upper surface portion of full width providing an approach and recession of the car wheel over the joint.

In testimony whereof, I have hereunto set my hand at San Diego, California, this 23d day of February, 1917.

CHARLES GARDNER.
